[57] CLAIM

The ornamental design for a three-component trash container, as shown and described.

DESCRIPTION

FIG. 1 is a front elevational view of a three-component trash container showing my new design, rear and side elevational view being a mirror image of that shown; FIG. 2 is an exploded front elevational view thereof; FIG. 3 is a top plan view of the container, shown with the lid and the bag holder removed;

FIG. 4 is a bottom plan view of FIG. 3;

FIG. 5 is a top plan view of the bag holder;

FIG. 6 is a front elevational view of FIG. 5;

FIG. 7 is a bottom plan view of FIG. 5;

FIG. 8 is a front elevational view of the trash container lid;

FIG. 9 is a top plan view of FIG. 8; and

FIG. 10 is a bottom plan view of FIG. 8.

FIG. 1**FIG. 2****FIG. 3****FIG. 4**

FIG. 5**FIG. 6****FIG. 7****FIG. 8****FIG. 9****FIG. 10**
